William P. Morrison, Mount Pleasant, Pa., assignor to Bryce Brothers Company, Mount Pleasant, Pa., a corporation of Pennsylvania

Application December 10, 1949, Serial No. 6,561

Term of patent 7 years

(Cl. D36—8)

To all whom it may concern:

Be it known that I, William P. Morrison, a citizen of the United States, residing at Mount Pleasant, county of Westmoreland, in the State of Pennsylvania, have invented a new, original, and ornamental Design for a Goblet or Similar Article, of which the following is a specification, reference being had to the accompanying drawing, forming a part hereof.

Figure 1 is a vertical view in elevation of a goblet, showing my novel design;

Figure 2 is a horizontal section taken along the line II—II of Figure 1; and

Figure 3 is a horizontal section taken along the line III—III of Figure 1.

The dominating features of the design are illustrated by the portions shown in full lines.

I claim:

The ornamental design for a goblet or similar article, as shown.

WILLIAM P. MORRISON.
